ROTARY IMPELLER BLADE

Henry E. Sanders, Kentwood, La.

Application May 15, 1939, Serial No. 273,741

4 Claims. (Cl. 170—159)

My invention relates to rotary impeller blades and methods of utilizing the same and while susceptible to many and varied uses, more particularly relates to impellers for aircraft, gas pumps, gas fans, and the like.

With the foregoing in view, an object of my invention is to provide an improved impeller blade.

A further object is to provide such a blade with a normal pitch and a reverse pitch embodied therein.

A further object is to provide such a blade with a normal pitch which gradually merges into a reverse pitch.

Other objects and advantages reside in the particular structure of my invention, combination and arrangement of the several parts and in the particular method of operation, all of which will be readily apparent to those skilled in the art upon reference to the attached drawing in connection with the following detailed description forming a part of this specification.

In the drawing:

Figure 1 is a side elevation of one form of my invention;

Figure 2 is a horizontal section taken on the line 2—2 of Figure 1;

Figure 3 is an end elevation of Figure 1;

Figure 4 is a side elevation of a modification; Figure 5 is an end elevation of Figure 4;

Figure 6 is a diagrammatic view similar to Figure 4 showing the method of operation; and

Figure 7 is a diagrammatic view similar to Figure 6 and showing the method of operation as applied to the form of invention of Figures 1 to 3.

Referring specifically to the drawing, wherein like reference characters have been used throughout to refer to like parts, 10 (Figs. 1-3) represents a drive shaft having one end connected to any suitable source of power (not shown). The free end of the shaft 10 has a block 12 fixed thereon for rotation therewith. A pair of blades 11 having hubs 14, each comprising spaced ears, are pivotally connected to the block 12 by bolts or the like 13. S-shaped bands 15 connect the hubs 14 together so that their inclination in use is the same at all times. The structure just described is substantially identical to that disclosed in my co-pending application, Serial No. 229,174, filed September 9, 1938. It is to be understood that as far as the balancing of the blades in use is concerned, this form of the invention functions like that embodied in the aforesaid co-pending application.

It will be noted that the free ends of the blades 11 are provided with the normal pitch for directing a current of air rearwardly parallel to the shaft 10 when the blades are rotated in a counter-clockwise direction. However, at least 5 of the rear surfaces 17a of the inner portions 17 of the blades are provided with a reverse pitch. Intermediate the normally pitched portions 16 and the reversely pitched portions 17 are portions 11a which are substantially parallel to the 10 plane of rotation of each blade and which have substantially no pitch but which merge in both directions into the respective pitches of the portions 16 and 17. This structure gives the blades a spirally twisted appearance in end elevation 15 (Fig. 3). It is to be noted, moreover, that the intermediate portions 11a may be substantially narrower than the portions 16 and 17 but diverge gradually in both directions to merge into the widths of these portions. The purpose of the 20 blade structure just described as well as its method of operating will be described later.

Figures 4-6 show a structure similar to that just described applied to an impeller having rigid blades. Here a rotatable shaft 20 is attached by suitable means 21 to the hub 23 of a two-bladed impeller 22. The outer portions 23 of the blades 22 have a pitch corresponding to that of the portions 16 of the first form of the invention, while at least the rear surfaces 24a of 30 the inner portions 24 have a similar reverse pitch. The intermediate portions 22a correspond in configuration to the portions 11a of the first form.

It is a well known fact that the air in front of an impeller begins to spiral before it is drawn 35 into the blades. It is possibly a not so well known fact that this spiralling body of air is in the form of a vortex, the apex of which is spinning at a much greater speed than are the outer portions. The action is like that familiar to 40 everyone in the draining of a wash basin through the bottom drain. In a rotary impeller, the reverse is true in that the tips of the blades are traveling at a higher rate of speed than the portions nearer the hub. As in the vortex, the 45 rotary speed progressively varies from blade tip to hub but in a reversed manner as the blade speed decreases towards the hub while the vortex speed increases towards the apex.

With respect to the vortex created by a rotary impeller blade, I have discovered that there is a definite relation between the spinning speeds of various portions of the vortex with respect to corresponding portions of the blades. That is to say, in the normal impeller—of, say an air- 55

craft—the outer portions of the vortex are spinning slower than the tip portions of the blades and are, therefore, driven by the blade pitch in a rearward direction. At some intermediate point a blade portion and a vortex portion are traveling at the same rate of speed in substantially the same direction so that the blade has little or not effect on that portion of the vortex. Finally, the apex portions of the vortex are spinning much faster than the corresponding inner portions of the blades. Thus, the apex portions of the vortex tend to drive the inner portions of the blade rather than be driven by them. However, as the normal blade at this point has the same pitch as tip portion, the spinning apex of the vortex encounters the nonworking face of the blade and is deflected forwardly rather than rearwardly and only goes rearwardly when it is drawn into the outer and more swiftly traveling blade portions. This phenomenon creates a low pressure area back of the blades in the region of the hub, limits the working area of the blades to the outer portions thereof and finally prevents adequate air cooling of the engine driving the impeller which is usually located in that region.

In Figures 6 and 7 I have diagrammatically illustrated the method of operation of both forms of my invention. Figure 6 is the form of Figures 30, 4 and 5 while Figure 7 is the form of Figures 1-3. In these figures, the vortex is diagrammatically illustrated at V and comprises a slowly spinning outer portion V¹ and a rapidly spinning apex V². The outer portion V¹ is driven rearwardly by outer blade portions 23 and 16 just as in the normal impeller. However, the inner vortex portions V² encounter the rear faces 17^a or 24^a of the reversely pitched portions 17 and 24 and are deflected rearwardly by them, it being remembered that the inner vortex portions V² are spinning faster than the blade portions 17 and 24 and overtake them. Thus, the high speed of the vortex apex is used to assist the motor while the reverse pitch of the blades at this point directs the vortex apex rearwardly along the shafts without directing it outwardly as in the usual blade, without causing a low pressure area behind the blades in the axial region. Moreover, cooling of the engine, or motor, by the slip stream is made more efficient and a greater proportion of the blade area is effectively utilized.

The intermediate portions 11a and 22a of the blades are relatively narrower than the end and inner portions 16, 23 and 17, 24 respectively. Also they have substantially no pitch because they are intended to be located at the point where the blade speed and the speed of the corresponding portion of the vortex are equal. The pitch and width of these portions increase in both directions to merge into the pitches and widths

of the outer and inner blade portions. Thus, where the blade and vortex speeds are equal there is substantially no resistance to the passage of the vortex through the blade, it being remembered that the vortex as a whole is moving axially of 5 the impeller—but at the points where there are relative differences between the spinning speeds of the vortex and blades pitched surfaces are provided to utilize this speed difference.

While in both forms of my invention I have 10 shown the front faces of the portions 17 and 24 as being reversely pitched as well as the rear faces 17^a and 24^a, it is obvious that this front pitch is not operative and may be dispensed with if it is found to be detrimental as it may well be 15 at certain speeds.

While I have shown and described what is now thought to be the preferred embodiments of my invention as applied to two-bladed impellers, it is obvious that my principle can be as well applied 20 to single bladed impellers, or impellers having more blades than two. Moreover, it is to be understood that my invention is not necessarily limited to impellers for aircraft but is believed to be equally applicable to impellers for gas pumps 25 or fans and possibly to marine propellers and fluid pumps and the like. Consequently it is not my intention to limit myself to the precise structures, uses and methods shown and described except as hereinafter claimed. 30

I claim:

1. A rotary impeller, comprising a shaft, at least one blade on said shaft, said blade including outer, inner and intermediate portions, the outer end of said outer portion having a finite 35 pitch, the inner end of said inner portion having a reversed finite pitch, said intermediate portion having substantially no pitch and lying in a plane substantially parallel to the plane of rotation of said blade, and the pitches of said outer 40 and inner blade portions gradually decreasing as they approach said intermediate portion and merging thereinto.

2. A rotary impeller comprising a shaft, at least one blade on said shaft, said blade including outer, inner and intermediate portions, the outer end of said outer portion having a finite pitch, the inner end of said inner portion having a reversed finite pitch, said intermediate portion having a zero pitch, the pitches of said inner and outer portions gradually decreasing as they approach said intermediate portion and merging thereinto. 45

3. The structure of claim 2, and said intermediate portion being substantially narrower than 55 said inner and outer portions.

4. The structure of claim 2, and means swingably connecting said blade to said shaft for movement about an axis at right angles to said shaft.

HENRY E. SANDERS. 60
